UNITED STATES PATENT OFFICE.

WILLIAM M. THOMAS, OF LOS ANGELES, CALIFORNIA.

REINFORCED-CONCRETE BRIDGE CONSTRUCTION.

1,329,643.

Specification of Letters Patent.

Patented Feb. 3, 1920.

Application filed February 11, 1915, Serial No. 7,455. Renewed June 25, 1919. Serial No. 306,716.

To all whom it may concern:

Be it known that I, WILLIAM M. THOMAS, a citizen of the United States, residing at Los Angeles, in the county of Los Angeles and State of California, have invented a new and useful Reinforced-Concrete Bridge Construction, of which the following is a specification.

This invention relates to three-hinge arch bridges built of reinforced concrete and the main object of the invention is to provide means at the hinge of the arch for giving a bearing which will result in most advantageous distribution of the strains and will prevent distortion or undue strains on the arch members.

Another object of the invention is to provide in connection with an arch of a reinforced concrete bridge a pier support having a hinge engagement with the arch which substantially eliminates bending or twisting strains due to unequalized bearings.

Another object of the invention is to provide, in a reinforced concrete bridge, means for temporarily mounting or engaging the several portions of such bridge in such manner as to provide for equalization of the bearing strains.

Other objects of the invention will appear hereinafter.

The accompanying drawings illustrate the invention, and referring thereto:

Figure 1 is a longitudinal vertical section of one span of a three-hinge arch bridge constructed in accordance with my invention;

Fig. 2 is a front elevation of one of the hinge bearing plates or members;

Fig. 3 is a side elevation of said bearing plate;

Fig. 4 is a side elevation of the ball or spherical bearing member for said hinge bearing;

Fig. 5 is a side elevation; and

Fig. 6 is a front elevation of a modified form of the spherical bearing member;

Fig. 7 is a side elevation, and

Fig. 8 is a front elevation of another modification of said bearing member;

Fig. 9 is a horizontal section through the hinge at the crown of the arch;

Fig. 10 is a vertical section through said hinge;

Fig. 11 is a horizontal section taken just

below the floor showing the arch and hinge thereof in plan;

Fig. 11^a is a vertical section of a modified form of the universal hinge-joint;

Fig. 12 is a vertical section of a portion of the span showing the application of my invention to the construction of an arch member for said span, the separate pre-formed portions and the means for temporarily mounting said portions bearing construction;

Fig. 13 is a section on line $x^{13}-x^{13}$, in Fig. 12;

Fig. 14 is a section on line $x^{14}-x^{14}$, in Fig. 12.

Referring to Figs. 1 to 11, the bridge 70 therein illustrated comprises piers or abutments 1 and a span extending between said piers or abutments and comprising two arch members each formed with arch beams or ribs 2 resting at their lower ends on said 75 piers or abutments and engaging at their upper ends by hinges as hereinafter described.

The hinges at the crown of the arch comprise ball or spherical members 10 and hinge 80 members 6 on the respective arch members 2. Each hinge member 6 may be formed as a plate of sufficient area to extend over substantially the end face of the arch rib or beam 2 so as to distribute the pressure 85 over said face, and said plate may be provided with flanges or plates 11 extending therefrom into the concrete 15 of the arch beam or rib; said plates or flanges 11 extending, for example, vertically and being 90 connected at their inner ends to horizontally extending plates or beams 16 whereby the bearing plates 11 are firmly tied or bonded to the concrete body of the arch beam or rib.

The reinforcing rods or members 13 of the 95 arch beam or rib are interconnected with these bearing plates by extending in a suitable manner between said plates and by cement molded in contact with said plates, rods and their connected metallic members. 100 In the front or outer face of each plate 6 is formed a socket or recess 6' formed as a portion of the surface of a sphere, and a ball or spherical bearing member 10 is adapted to fit and engage in said socket or 105 recess in each bearing plate so that the bearing engagement or connection between the two arch rib members at the crown of the

arch is through the spherical bearing members 10, one of said bearing members being provided for each pair of opposed arch ribs 2. By means of this construction a bearing 5 or hinge joint is provided between the two arch members such that the pressure is brought wholly on these spherical bearing members, which adjust themselves in such manner that there is no lateral or distorting 10 strain tending to bend or break the arch beams.

The arch beams or ribs 2 rest at their ends on the piers 1 by suitable hinge bearings. For example, as shown at the left of Fig. 1, 15 said beams or ribs may be provided with hemispherical end bearing portions 9 fitting in correspondingly formed hemispherical sockets or seats 10' on the bearings; or as shown at the right on Fig. 1, this bearing 20 hinge may be formed similarly to the crown hinge comprising a ball or spherical member 14 fitting in sockets 15 on hinge plates 7 secured respectively to the lower end of the arch rib member 2 and to the upper face 25 of the bearing; suitable means 8 being provided for bonding or tying these plates 15 to the beam and pier respectively, and said plates being of sufficient area to distribute the pressure over the beam or the pier, as 30 the case may be. The arch beams 2 are connected by the diaphragms or spacing members 3 and 5. Said spacing members 3 support spandrel posts or columns 4, the floor member 12 being carried by the diaphragms 35 or transverse beams 5 and by beams 5' at the upper ends of said spandrel members.

Retaining means may be provided at the hinge joint for preventing the arch members from being violently separated to a 40 sufficient extent to allow the spherical bearing member 10 to become dislodged; said means consisting of bolts 18, sliding through openings in fittings 19 on hinge members 6, and adapted to engage said fittings by heads 45 18' and nuts 19' on said bolts, to limit the separation of the arch members.

The bearing member 10 for the hinge joint aforesaid may consist of a sphere or ball of suitable metal, such as steel or iron; 50 or it may, as shown in Figs. 5 and 6, consist of a lens-shaped body of suitable metal having bearing faces 20 formed as segments of spheres, the sockets in the hinge members being, in that case, correspondingly formed; 55 or as shown in Figs. 7 and 8, said bearing member may consist of a block having squared side faces 22 and having its end or bearing faces 23 formed as segments of spheres. In any case, the effect is to 60 provide bearing faces formed as portions or segments of spheres providing a universal joint bearing which allows self adjustment of the arch members thereto, so as to give a uniform or equalized bearing throughout 65 the area of contact. As shown in Fig. 11^a,

the universal hinge joint may comprise an intermediate member 45, and ball members 46 fitting in ball sockets 47 in the hinge members 48 and 49 and in said intermediate member.

My invention may also be applied in the construction of bridges to facilitate the mounting of the parts into proper position. Thus, as shown in Fig. 12, the arch beams are of such large size as to render it 75 desirable to build each beam in pre-formed sections which are subsequently assembled to form the beam. Such sections indicated at 24 may be connected by hinge joints similar to those above described. For this purpose each beam section 24 is provided at each end with a bearing plate 25 tied to the body of the beam by metallic tie means 26 and provided with a seat or recess 27 on its outer face, adapted to receive and fit a ball 80 or spherical bearing member 28. Suitable tie means, such as tension rods 29, provided with turnbuckles 30, are used to connect the bearing plates 25 on opposite sides of the joint. In assembling the arch rib the arch 85 rib or beam members 24 are supported temporarily in proper position by false work or temporary supporting means indicated at 33 and 34. The balls or spherical bearing members 28 are placed in position in the seats or 90 sockets of the opposing bearing members 25 and the tension rods 29 are tightened up by means of turnbuckles 30 so as to bring and hold the parts to proper relative position. Cement is then poured into the space around 95 the parts 25, 30, as indicated at 35, so as to embed the same and form an integral rigid arch beam, the bearing being mainly for the purpose of facilitating setting up of the parts of the beam but also serving eventually as a portion of the beam structure and serving to equalize the strains at that portion of the beam throughout the cross section of the beam.

As shown in Figs. 12 and 14 a similar ball hinge construction may be used in mounting the spandrel columns indicated at 100 36, said spandrel column and the supporting portion of the transverse beam or spandrel member 37 being provided with bearing plates 39 having recesses 40 fitting the spherical bearing member 41, said plates 39 being tied together by tension rods 42 provided with turnbuckles 43 whereby the post may be drawn tightly to proper position. 115 When the post has been set up in this manner, cement is poured into and around the joint as at 44 to embed the metallic parts aforesaid and form an integral rigid post.

What I claim is:

1. In a reinforced concrete bridge construction, the combination of two arch members provided with hinge means forming a bearing between said members, said hinge means comprising spherical bearing surfaces 130

to provide for equalization pressure over the bearing surfaces.

2. In a reinforced concrete bridge construction, the combination of two arch beams provided with hinge means for giving a hinge bearing between said members, said hinge beams comprising plates for distributing the bearing over said arch members, a ball and socket means on said plates 10 providing a universal joint bearing between the said arch members.

3. In a reinforced concrete bridge construction, the combination of reinforced concrete arch members, plates on said members and tied thereto, said base being provided with bearing sockets formed with spherical surfaces, and a bearing member interposed between said plates and having spherical surfaces fitting in said sockets.

20 4. In a reinforced concrete bridge construction, the combination of two bridge members, ball and socket means on said members for giving a universal joint bearing between said members, and tie means 25 connecting said members.

5. In a reinforced concrete bridge construction, the combination of two reinforced concrete bridge members, bearing plates on the respective members provided with ball sockets, a spherical bearing fitting in said 30 sockets, tie means connecting said plates, and cement molded over and embedding said tie means and bearing members.

6. In a reinforced concrete bridge construction, the combination of two arch members, ball and socket hinge means between said members, providing a universal hinge joint therefor, and metallic means extending between said members and adapted to engage said members with a limited amount 35 40 of play to limit the amount of separation of said members.

In testimony whereof I have hereunto set my hand at Los Angeles, California, this 2d day of February, 1915.

WILLIAM M. THOMAS.
